UNITED STATES PATENT OFFICE.

GEORGE P. FENNER, OF NEW LONDON, CONNECTICUT.

SHEET-DELIVERY APPARATUS.

SPECIFICATION forming part of Letters Patent No. 345,222, dated July 6, 1886.

Application filed September 3, 1885. Serial No. 176,084. (No model.)

To all whom it may concern:

Be it known that I, GEORGE P. FENNER, a citizen of the United States, residing at New London, in the county of New London and State of Connecticut, have invented new and useful Improvements in Sheet-Delivery Apparatus, of which the following is a specification.

My invention relates to improvements in sheet-delivery apparatus for printing-presses, which improvements are especially adapted to stop-cylinder presses; and it consists, essentially, in a carrier-reel adapted to directly receive the printed sheet from the impression-cylinder and deliver the said sheet upon a receiving-table properly located to receive the same. The carrier-reel is operated by suitable levers and cams, which connect the same with the main shaft of the press.

The specific construction of the carrier-reel and the other operating parts is more fully pointed out in the following specification and claims, and illustrated in the accompanying drawings, in which—

Figure 1 is a side elevation of a printing-press provided with my improved sheet-delivery apparatus. Fig. 2 is an end elevation of the same. Fig. 3 is a plan or top view of the mechanism for locking the carrier-reel and carriage.

Similar letters indicate corresponding parts.

In the drawings, the letter A designates the press-frame, constructed to support the impression-cylinder B and type-bed C in the proper relation to each other. At one end of the press-frame are bearings for the driving-shaft D, from which motion is transmitted by gear-wheels D' D² to the main shaft E of the press, and from which shaft E motion is in turn transmitted by the usual crank, E', and connecting-rod E², Fig. 1, to the traveling rack-wheel E³, which meshes into a stationary rack, E⁴, on the base of the press, and also engages a suitable rack, E⁵, which is pendent from the type-bed C, whereby a reciprocating motion is imparted to the said type-bed. The impression-cylinder B receives its motion from the type-bed C through a second rack, C', which is suitably arranged upon the said type-bed C to engage with the cog-wheel B' of the impression-cylinder in the usual manner. A portion of this cog-wheel B' is cut away, so as to permit the type-bed C to travel while the

cylinder is at rest during stated intervals. At a point back of this space in the wheel B the impression-cylinder carries a catch, F, which is adapted to be engaged by a catch-lever, F', which operates to check, hold, and start the impression-cylinder under the impulse of adjusting mechanism of well-known construction. In the example shown in the drawings this catch-lever is pivoted at f to the press-frame, and is vibrated by means of a cam, F², which has a suitable way therein, and a rod, F³, connected at one end to the lever, which has on its other end a roller-stud, f', which engages with the way in the cam F². The end of the rod F³, which carries the roller-stud f', is slotted or bifurcated, so as to clear the main shaft E, and in order to support the former a block is neatly fitted into the slotted portion, through which block the shaft passes, the whole being arranged to allow the uninterrupted motion of the connecting-rod F³. The impression-cylinder is provided with suitable grippers, B², for holding the sheet to be printed upon the cylinder, these grippers B² being opened by stationary trip cams or posts B³ B⁴, arranged on the press-frame in their proper relative position, and closed by suitable springs, as usual, the whole constituting the main features of a stop-revolution press of well-known construction.

G G are a pair or racks, secured to the press-frame A in a proper alignment with the impression-cylinder, which racks are arranged directly over the receiving-table H, which is also properly secured to the frame, and these racks G G are engaged by gear-wheels I I, which gears I I and their shaft I' support a carrier-reel, J, which is constructed to receive the printed sheet from the impression-cylinder B, and transfer the same to the receiving-table H, previously mentioned. The gears I I and their shaft, I, shall hereinafter call the "reel-carriage." The gear-wheels I I, as before stated, are mounted upon a shaft, I', which extends through a hollow spindle, K, Fig. 2, which spindle can rotate about the shaft I', and carries upon one end a gear-wheel, K', which is constructed to engage at the proper time with a corresponding gear-wheel, K⁵, upon the impression-cylinder B, so that a rotary motion is imparted to the spindle K, while the inner shaft, I', and the gear-wheels I I upon

the said inner shaft remain stationary in the position shown by full lines in Fig. 1 until acted upon by mechanism which will be hereinafter described.

5 To receive the paper from the impression-cylinder, two disks, K² K², Fig. 2, are arranged upon the hollow spindle K, which disks can be adjusted toward or from each other and secured in such a position by suitable thumb-screws or the like. The adjustment of the disks is rendered necessary to adapt the sheet-delivery apparatus for varying widths of sheets. A third disk, K³, is arranged and permanently secured to the spindle K, the said disk K³, however, only acting as a base for the sheet-grippers, which will be hereinafter more fully described.

It will be observed that, in order to properly deliver the sheet from the impression-cylinder 20 B to the receiving-table H, the said operation must be accomplished while the cylinder is at a stop, and that the carrier-reel J must be returned to its original position in time to receive the next printed sheet. This motion at 25 the proper interval is imparted to the carrier-reel, as follows: To the main shaft E of the press is secured a heart-cam, I², which rotates with the said shaft, and engages with a roller-stud, I³, having bearings on the lower arm of 30 a lever, I⁴, which is fulcrumed to the frame at i⁴. This lever extends upward toward carrier-reel J, and its upper arm is connected with a link, I⁵, which extends to and is in connection with the shaft I¹, carrying the gears I I. To 35 continually keep the roller-stud I³ on the lower arm of lever I⁴ in close contact with the cam I², I employ a rod, I⁶, which is connected to the other arm of the lever I⁴, and extends through a socket, i⁶, on the frame of the press, 40 and which rod I⁶ has a collar, i⁷, thereon, which is subjected to the action of a spring, I⁷, coiled around the rod I⁶, and abutting, respectively, against the socket i⁶ and collar i⁷, the action of the spring being in the proper 45 direction to produce the desired result. However, other means which would suggest themselves to a skilled mechanic could be employed to effect the same result.

The means for removing the printed sheet 50 from the impression-cylinder B, retaining the same on the carrier-reel J, and releasing the said sheet at the proper moment from the carrier, consists of a set of grippers, M, Fig. 2, mounted upon a gripper-shaft, M', the said 55 shaft having bearings in the gear-wheel K' and disk K³, which are mounted on the said shaft. These grippers M are operated by a lever, M², fulcrumed to the disk K³, which is subjected to the action of a suitable spring in the ordinary manner, and is adapted to be engaged by a trip-cam, M³, secured to the receiving-table H, and also by a suitable cam, M⁴, and the ends of these grippers impinge upon the edge of a radial web, K⁴, extending from the spindle and across the reel, so as to clamp the edge 60 of the paper between the grippers and the

web K⁴. To allow the use of such an arm or partition, the disks must necessarily be slotted. As before stated, the disks K² K² and disk K' can rotate independently of the shaft 70 I' and the gears I I thereon. In other words, the carrier-reel J can rotate independently of the carriage; but when the printed sheet is ready for delivery to the receiving-table, and during the linear motion of the reel, it is necessary that the carrier-reel should not rotate independently, but participate in the rotation of the gears I I. For this purpose some locking device must be employed, and in the example shown in the drawings I have made 75 use of the following: Upon the main shaft E of the press is secured a bevel-gear, N, which meshes into a similar gear, N', situated upon a counter-shaft, N², aligned at right angles to the former shaft, E, and which shaft has suitable bearings in the press-frame. This counter-shaft N² has thereon a cam, N³, which engages a roller-stud, n³, secured to one end of a rod, N⁴, which rod is suitably bifurcated to straddle the shaft at this point, and the upper 80 end of this rod N⁴ is connected to a lever, N⁵, which is fulcrumed at n⁵ to the press-frame, while its other end is provided with an inwardly-extending projection, n⁶, which engages with a pin, n⁶, upon one arm of a lever, 85 N⁶, pivoted at or near its center to the gear-wheel I. The lever N⁶ is provided with this inwardly-extending projection n⁶ in order that when the reel-carriage moves forward in its linear motion toward the receiving-carriage 90 H the said lever N⁶ will not interfere with its motion. As the carrier-reel is thus drawn forward by the link I⁵, the pin n⁶ clears the projection n⁶ of the lever N⁶. The lever N⁶ is subjected to the action of a spring, n⁷, which 95 constantly tends to keep the same in contact with the lever N⁵ when opposite thereto. The pin n⁶ extends through a slot, n⁸, Figs. 1 and 3, in the gear-wheel I, to allow the lever to swing about its fulcrum, and engages at the 100 proper intervals with a catch, n⁹, on the gear-wheel K', thereby automatically locking the two gears, and producing the desired result. When the roller-stud n³ on the rod N⁴ is not engaged by the cam, the gears and the reel are 105 locked; but when the said rod is so engaged by the cam N³ the lever N⁶ is raised, and the pin n⁶ is thrown clear of the catch n⁹, whereby the same is released from the cam, and the designated parts can again rotate independently 110 of each other.

The operation of the press is now as follows: In the drawings the working parts of the press are shown in the position they will be in when the press has finished printing the sheets and the impression-cylinder is in such a position that the grippers B² thereof are ready to grasp the next sheet and a sheet is under the grippers of the paper-carrier reel. When the main shaft E now continues its motion in the direction of arrow 1, the type-bed C moves toward the impression cylinder B in the direction of arrow 115

2 marked thereon, but does not rotate the impression-cylinder, since the latter is not rotated by the catch-lever F so as to bring its teeth in contact with the rack C until the shaft E has 5 made one-half of a complete revolution, which fact is due to the contour of the cam F², and consequently the cylinder remains stationary until the bed has reached its extreme position on the opposite side of the impression-cylinder. During the semi-revolution of the main shaft and the traverse of the bed the hollow portion of the heart-cam I² is brought toward the roller-stud I³, on the lever I⁴, and, owing to the action of the spring I⁷, the upper arm of the lever I⁴ is pushed outward in the direction indicated by arrow 3, carrying with it the carrier-reel J, the gears I I of which engage and travel along the racks G G. Just before the carrier-reel starts in its linear motion, the pin n³ of 20 the lever N⁴ is released from the cam N³ on the shaft N², whereby the gears and the gear and disks of the carrier-reel are locked. The lever I⁴, being moved outward from the impression-cylinder, carries the carrier-reel therewith, 25 the disks now rotating with the gear-wheels I I until both have reached the position indicated by dotted lines in Fig. 1. During this traverse the grippers M on the shaft M² are opened by the lever M³ coming into contact with the 30 spur or cam M³ on the receiving-table, so that the end of the sheet is released, the sheet then falling printed face upward upon the delivery-table. On the remaining semi-revolution of the main shaft E the carrier-reel J is returned to its normal 35 position in contact with the impression-cylinder. The carrier-reel and the reel-carriage gears I I are again unlocked, in order to allow the reel to rotate with the said impression-cylinder, and the type-bed moves toward 40 its original position, as shown in the drawings, but in so doing it engages with the cog-wheel B' of the impression-cylinder, which has been previously sufficiently turned by the 45 action of the lever F², and when in the position shown in the drawings the grippers B² are again in position to grasp the sheet delivered thereto from the feed-table. Since the carrier-reel J participates in the rotation of the 50 impression-cylinder, the forward edge of the sheet printed during the preceding operation is grasped by the grippers M of the carrier-reel J, which draw the same upon the carrier-reel, whence it is delivered, as before described. 55 Since only two disks, K' K², are used in the construction of the sheet-carrier, only the edges of the paper come in contact with the said reel, and consequently the printed face is delivered unsmeared from the said reel to the 60 receiving-table. As before stated, the sheet is held to the carrier-reel only along one of its edges, the lower edge of the sheet being free; but the entire sheet holds itself closely around the disks of the said carrier-reel during the operation of delivering the sheet to 65 the receiving-table, and the free end of the

sheet does not release itself from the carrier-reel until it arrives at the proper position to fall upon the table.

I do not claim the combination, with an impression-cylinder, of a carrier-reel and a reciprocating carriage supporting the carrier-reel.

What I claim as new, and desire to secure by Letters Patent, is—

1. The combination, with the impression-cylinder, of the reel-carriage having an intermittent motion toward and from the cylinder, a carrier-reel supported by said reel-carriage and adapted to be rotated by the impression-cylinder to receive the sheet, substantially as shown and described. 75

2. The combination, with the impression-cylinder, the receiving-table H, and the trip-cam M³ thereof, of the reciprocating carrier-reel and the grippers M and web K⁴ thereof, for retaining and releasing the paper, substantially as shown and described. 85

3. The combination, with the impression-cylinder and the receiving-table H, of the carrier-reel J, the supporting-carriage, the rotary cam I², and the lever-connections of the carriage, with the cam for imparting to the carriage a reciprocating motion, substantially as shown and described. 90

4. The combination, with the impression-cylinder, the receiving-table H, the racks G G, and the carrier-reel J, of the gears I I and shaft I⁴, forming the reciprocating carriage, and means, as described, for locking the carrier-reel and carriage, substantially as shown and described. 100

5. The combination, with the carrier-reel J, of the shaft I⁴ and gears I I thereon supporting the said carrier-reel, the rotary cam N², the rod N⁴, engaging the cam-lever N⁵, and the lever N⁶ on the gear I, adapted to engage with a catch, n³, on the reel, substantially as shown and described. 105

6. The combination, with the impression-cylinder, the carrier-reel J, rotary cam I², and carriage, of the racks G G, gears I I, engaging the racks, gear K', engaging the impression-cylinder, and spring-pressed lever I⁴, connected with the carrier and engaging the cam, substantially as shown and described. 110

7. The combination, with the reel-carriage, of the disks K' K², adjustable on a spindle encompassing the shaft of the reel-carriage, and the grippers for retaining and releasing the sheet, substantially as shown and described. 120

8. The combination, with the reel-carriage, of the disks K' K², adjustable on a spindle encompassing the shaft of the reel-carriage, the grippers M on shaft M², and web K⁴, for retaining and releasing the edge of the sheet, and a gear, K', and disk K³, having bearings for the gripper-shaft, substantially as shown and described. 125

9. The combination, with the impression-

cylinder and the gear K⁵ thereof, of the reciprocating carrier-reel J, having a gear, K', adapted to engage with the gear on the impression-cylinder, substantially as shown and described.

10. The carrier-reel J, mounted in a reciprocating carriage and constructed to rotate independently of the carriage, and means for locking the carrier-reel to the carriage, substantially as set forth.

In testimony whereof I have hereunto set my hand and seal in the presence of two subscribing witnesses.
